UNITED STATES PATENT OFFICE.

ANDREW FOLLWEILER, OF HENRYVILLE, PENNSYLVANIA.

VENTILATOR.

1,262,032.

Specification of Letters Patent. Patented Apr. 9, 1918.

Application filed July 18, 1916. Serial No. 109,920.

To all whom it may concern:

Be it known that I, ANDREW FOLLWEILER, a citizen of the United States, residing at Henryville, in the county of Monroe and State of Pennsylvania, have invented certain new and useful Improvements in Ventilators, of which the following is a specification.

This invention relates to ventilators and more particularly to a ventilating device 10 which is particularly adapted to be employed in connection with railway cars.

The primary object of the device is to provide a ventilator that will create suction within the car whereby the foul air and dust 15 will be withdrawn from the interior of the car and ejected therefrom.

A further object of the invention contemplates the provision of a pair of oppositely disposed members which are mounted on the 20 exterior of the car and adapted to receive the air as it rushes along the side of the car whereby a suction of considerable force will be obtained within the car for effectively withdrawing the foul air therefrom.

25 A further object of this invention is the provision of a ventilator which consists of comparatively few parts and is simple in construction, but durable and well adapted to withstand the rough usage to which devices 30 of this character are ordinarily subjected.

For a full description of the invention and the advantages and merits thereof, reference is to be had to the following description and the accompanying drawings, where- 35 in is illustrated the preferred form of my invention, in which;

Figure 1 is a fragmentary vertical section through the upper portion of a car showing the ventilator applied thereto.

40 Fig. 2 is a section on the line 2—2 of Fig. 1.

Fig. 3 is a section on the line 3—3 of Fig. 2.

Fig. 4 is a section on the line 4—4 of 45 Fig. 2.

As shown by Fig. 1 of the drawing the ventilator is arranged near the top or roof A of the car and the air conveying pipes extend through the side walls B thereof and 50 carry the suction creating devices which are disposed on the exterior of the car. Directly below the center of the roof A, on the interior of the car, is an intake funnel 1 which is provided with the funnel-shaped 55 mouth 2 and the spherical body portion 3 the top of which is in engagement with the

roof A. Oppositely disposed screw threaded apertures formed in the spherical body portion 3, receive the air conducting pipes 4 which have their opposite ends extending 60 through openings in the side walls B of the car. Right-angle elbows 5 are screw threadedly engaged with the ends of the pipes 4 and are adapted to support the suction creating devices, designated in their entirety by 65 the numeral 6.

One of the suction creating devices 6 is arranged on each side of the car and each device consists of a cylindrical drum 7 which is reduced in diameter at one end and provides the tubular neck 8. Integrally formed with the drum 7, at opposite sides thereof, are the funnels 9 which communicate with the interior of the drum 7 and are disposed in a position to extend longitudinally of the 75 car whereby one of the funnels will receive the air as it rushes by while the car is in motion. Two funnels are provided in order that the air may be received, regardless of the direction in which the car is traveling. 80

The top end wall 10 of the drum is provided with a central screw threaded opening which receives one end of the air ejecting pipe 11, the opposite end of which terminates slightly above the opening in the end 85 of the neck 8. The screw threaded end of the pipe 11 is extended slightly beyond the upper end of the drum whereby it may be received in the end of the elbow 5. The suction devices are thereby supported without 90 the use of fastening elements.

In order that the air, as it passes into the drum, through one of the funnels 9, may be directed downwardly through the neck 8, I provide a pair of partitions 12 as clearly 95 shown in Figs. 2 and 4 of the drawing. These partitions 12 are disposed vertically and extended for the full length of the pipe 11 and transversely across the drum 7 and neck 8. The air is thereby directed downwardly through the drum and neck and creates a powerful suction which draws the air through the pipe 11 thereby creating a suction within the car which will be maintained as long as the car is in motion. 105

From the foregoing it will be observed that a very simple and durable ventilator has been provided, the details of which embody the preferred form. I desire it to be understood however, that slight changes in 110 the minor details of construction may be made without departing from the spirit of

the invention of the scope of the claim hereunto appended.

I claim:

A car ventilator comprising a cylindrical drum mounted at the side of the car and disposed in vertical position and including a lower portion of a diameter less than the diameter of the upper portion, the latter having oppositely projecting funnels communicating with the interior of the drum, partitions arranged within the drum and laterally spaced apart and terminating in spaced relation to the end of the said lower portion of the drum, for forming a plurality

of separate spaces extending longitudinally 15 within the drum, and a suction pipe disposed in the central space between the two partitions and extending upwardly through the top of the said drum and having its lower end terminating flush with the lower 20 end of the said partition.

In testimony whereof I affix my signature in presence of two witnesses.

ANDREW FOLLWEILER.
